[57] CLAIM

The ornamental design for a hangable organizer for bows, earrings, and hair clips, as shown and described.

DESCRIPTION

FIG. 1 is a front perspective view of the hangable organizer for bows, earings, hair clips and similar accessories showing my new design, a rear perspective view being identical;

FIG. 2 is a side elevation view thereof;

FIG. 3 is a top plan view thereof; and,

FIG. 4 is a bottom plan view thereof.
